UNITED STATES PATENT OFFICE.

OTTO NIEDERER, OF TITUSVILLE, NEW JERSEY.

BUTTON.

Application filed January 4, 1926. Serial No. 79,111.

The present invention relates to improvements in buttons, of the type used on garments, and consists in the combinations and arrangements hereinafter described and particularly set forth in the accompanying claim.

The purpose of the invention is to produce a button of the kind especially adapted for use on nether garments that are subjected to the action of wringer rollers in the process of laundering, to the end that said buttons may safely pass through the rollers of the wringer without breaking the buttons or injuring the material of the rollers.

Another characteristic of the invention is that the material of the button has incorporated therein a heat resistant substance so that there will be no deterrent effect incident to the usual heat to which such buttons are subjected in the ordinary process of washing and drying.

The invention is shown by way of illustration in the accompanying drawing, wherein:

- Figure 1 is a top plan view of the button;
 Figure 2 an edge elevational view thereof; and,
 Figure 3 a transverse sectional view of the same.
- Referring to the construction in further detail, and wherein like reference characters designate corresponding parts in the different views shown, 4 indicates the button of ordinary size that is attached by sewing, or otherwise, to the fabric 5 of the garment. And it is proposed, of course, that buttons of this material be used throughout the garments in lieu of the ordinary buttons now employed.
- The annular marginal portion 6 of the button is of gradually tapering form, as shown, and the entire top or exposed sur-

face has a smooth and unbroken finish so that the entire button body may easily enter and pass between the rollers of the wringer without injury to either the button or the wringer.

A shank-like portion 7 is formed integral with the button body and is relatively short for obvious reasons. Suitable apertures 8 are formed for the stitches 9 as shown.

With substantially this configuration or design the button is made of soft pliable rubber and has incorporated therein, during the process of making, an appreciable quantity of finely comminuted asbestos or other heat resistant substance. Suitable proportions of rubber and asbestos are approximately seventy-five percent (75%) and twenty-five percent (25%) by volume respectively.

It is to be understood that the invention as herein disclosed is not limited to the details of construction shown and described as these may be varied widely without departing from the spirit of the invention as defined by the claim.

What is claimed as new is:

An improved button constructed of pliable and heat resisting material having a convex top with a smooth unbroken finish, said top gradually tapering down to a relatively thin marginal edge, the bottom being flat and provided with a wide, shallow, flat faced hub, through running apertures being provided near the center of the button, said apertures being cross-connected to house suitable fastening means below the convex top surface, substantially as set forth.

In witness whereof, I have hereunto set my hand at Washington, D. C., this twenty-third day of December, A. D. nineteen hundred and twenty-five.

OTTO NIEDERER.
